UNITED STATES PATENT OFFICE.

AUGUST J. BISCHOFF, OF CHICO, CALIFORNIA.

HYDROCARBON-BURNER.

1,169,916.

Specification of Letters Patent.

Patented Feb. 1, 1916.

Application filed February 23, 1915. Serial No. 9,857.

To all whom it may concern:

Be it known that I, AUGUST J. BISCHOFF, a citizen of the United States, residing at Chico, in the county of Butte, State of California, have invented certain new and useful Improvements in Hydrocarbon-Burners: and I do declare the following to be a full, clear, and exact description of the same, reference being had to the accompanying drawings, and to the characters of reference marked thereon, which form a part of this application.

This invention relates to improvements in liquid fuel burners and particularly to a hydrocarbon burner adapted for using distillate and similar fuel oils, the object of the invention being to produce a novel retort for gasifying fuel in combination with a new arrangement of storage retorts and burners.

A further object of the invention is to produce a simple and inexpensive device and yet one which will be exceedingly effective for the purposes for which it is designed.

These objects, I accomplish by means of such structure and relative arrangement of parts as will fully appear by a perusal of the following specification and claim.

In the drawings similar characters of reference indicate corresponding parts in the several views.

Figure 1 is a top plan view of the complete burner, for cook stoves, etc. Fig. 2 is an end view of the same. Fig. 3 is a sectional view taken on a line X—X of Fig. 1. Fig. 4 is a sectional view taken on a line Y—Y of Fig. 1.

Referring now more particularly to the characters of reference on the drawings, my invention embodies primarily a starting or dripping pan 1. Disposed across this dripping pan 1 are suitable supporting brackets 2. Mounted on the brackets 2 at each end of the pan 1 is a pair of storage gas receptacles, those at one end being designated by the numerals 3 and 4, and those at the other end being designated by the numerals 5 and 6.

The numeral 7 designates the gasifying retort which is composed of an integral member divided into four chambers, 8, 9, 10 and 11 respectively, the member 7 being cut away along a portion of its length to form spaces 12 between the said four chambers. In practice the retort 7 is set above the pan 1 and to one side thereof. Each of

the chambers 8, 9, 10 and 11 respectively has an independent fuel inlet pipe designated in the drawings as 13, 14, 15 and 16 respectively, each of said inlet pipes having a control valve 13^a, 14^a, 15^a and 16^a respectively 60 whereby the admission of the fuel into any one of the chambers of the retort may be controlled for a purpose as will appear.

As will be noted, the inlet pipes just described communicate with one end of their respective chambers. Thus the fuel is admitted through the pipe 14 into one end of the chamber 9 and passes through said retort where it is gasified with the heat applied against it in a manner as will appear, 70 which gas passes out the other end of said chamber 9 through a pipe 17 which communicates with a storage gas receptacle 5 where the gas can accumulate in a quantity and be used therefrom through a nozzle 18 which 75 throws the flame against a spreader plate 19 clamped to the pipe 16 above the nozzle 18.

The fuel admitted through the pipe 13 into the chamber 8 is likewise gasified in the said chamber 8. It then passes out 80 through a pipe 20 connected with the other end of the chamber 8 which pipe 20 leads to the storage receptacle 6. A vertical outlet pipe 21 leads upwardly from the end of the receptacle 6 and is provided with an elbow 22 at its upper end connected into which is a discharge nozzle 23 directed in such a manner as to throw the flame of the ignited gas passing therethrough directly against the retort 7 and more particularly directly 90 into the spaces 12 between the various chambers of said retort, the edges 12^a of said spaces 12, being flared outwardly as shown in Figs. 1 and 3 so as to aid in directing the flames into the spaces 12 and at the same 95 time give a greater heating surface for the various chambers.

As will be noted the discharge nozzle 18 forms a central burner while the effect of the discharge nozzle 23 is to form a side 100 burner so that when the device is installed in a cooking stove there will be a direct flame under the front heating plates and likewise a side flame furnished across the balance of the stove. Each of the nozzles 105 18 and 23 is provided with a straining wire mesh 24 in rear of its outlet and the base of each nozzle is further filled with an asbestos filler 25 so as to act as a filter for the gas passing therethrough to segregate the car- 110

bon from the gas, and the members 21 and 22 are likewise filled with this asbestos filler as shown clearly in Fig. 4.

As is shown in the drawings, each complete burner consists of a duplication of structure on each end and therefore the fuel enters through a pipe 15 into the chamber 10 at one end, passes through said chamber where it is gasified, which gas passes out 10 the other end through a pipe 27 and thence into the storage receptacle 3, which it passes out through a discharge nozzle 28 located under the spreader 29 clamped as at 30 to the pipe 13. The fuel passing through the 15 pipe 16, enters the chamber at 11 at one end, passes through said chamber where it is gasified, the gas passing out a pipe 31 at the other end of the chamber 11, which pipe 31 connects with the storage receptacle 4. 20 From this receptacle 4 a vertical discharge pipe 32 extends upwardly and is provided with an elbow 33 having a discharge nozzle 34 constructed similarly to the nozzle 23 and disposed in a similar manner to discharge 25 against the retort 7 all for the purpose previously described in connection with the nozzle 23. Said nozzle 34 and its connections are likewise filled with the filtering substance to remove the carbon from the 30 gas. Each of the chambers of the retort 7 and each of the storage receptacles is provided with a removable plug at each end as shown by the numeral 35, these plugs to be removed for the purpose of cleaning out 35 the various chambers and retorts.

From the description here given it will be seen that the retort 7 will receive the benefit of all the heat derived from the combustion of the gases, and at the same time all 40 the pipe connections will be subject to the direct heat of the flames, which will tend to highly gasify the fuel and at the same time leave the flames as spread by the spreader members 19 and 29 free to play directly 45 against the top of the stove, while the flames from the other discharge members 23 and 34 will pass through the spaces 12 in the retort 7 and thence heat the balance of

the stove. One of the main and essential features of my improved burner is that of 50 having the gasifying retort and the storage receptacle separate and spaced one above the other respectively so that practically nothing except clean gas free from carbon deposits will be carried by the storage receptacle and at the same time the storage receptacle provides a pressure equalizing chamber for its jet. 55

From the foregoing description it will be readily seen that I have produced such a 60 device as substantially fulfills the object of the invention as set forth herein.

While this specification sets forth in detail the present and preferred construction of the device, still in practice such deviations from such detail may be resorted to as do not form a departure from the spirit of the invention, as defined by the appended claim. 65

Having thus described my invention what 70 I claim as new and useful and desire to secure by Letters Patent is:

A device of the character described comprising the combination of a plurality of storage receptacles, a gasifying retort disposed above and to one side of said storage receptacles, said gasifying retort being divided into a number of chambers equal to the number of said storage receptacles, an independent fuel supply pipe communicating with each chamber, a discharge pipe leading from each chamber to one of said storage receptacles, each storage receptacle having an independent discharge nozzle, a portion of said discharge nozzles extending 75 vertically and the balance extending vertically and then at right angles to throw the discharge directly against said gasifying retort, as described. 80

In testimony whereof I affix my signature 85 in presence of two witnesses.

AUGUST J. BISCHOFF.
